UNITED STATES PATENT OFFICE.

CAMERON TURNER, OF BEVERLY, MASSACHUSETTS, ASSIGNOR TO UNITED SHOE MACHINERY CORPORATION, OF PATERSON, NEW JERSEY, A CORPORATION OF NEW JERSEY.

CUSHION HEEL.

Application filed March 26, 1923, Serial No. 627,735. Renewed January 28, 1929.

This invention relates to cushion heels and has particular reference to the provision of improved means for anchoring the heads of the fastenings in rubber or other similar cushion heels which are to be attached to 5 shoes by nails or like headed fastenings.

The almost universal practice in the past has been to embed in a rubber heel, at the locations where the attaching nails were to be driven, a plurality of separate, isolated washers through which the nails were driven and which prevented the nail heads from pulling through the rubber body of the heel. The placing of these washers upon the supporting pins in the mold in which the heel is vulcanized during the process of its manufacture consumes a great amount of time, and the labor cost of this operation is an important factor in the total manufacturing 20 cost of rubber heels. Furthermore, while the washers perform their intended function fairly well, they not infrequently become loosened from the rubber, whereupon their effectiveness is greatly decreased.

Attempts have been made to overcome the drawbacks referred to by employing a metallic skeleton plate or a piece of fibrous material, as a substitute for the washers. The metallic plate, if it be of sufficient area to receive all the attaching nails, is objectionable because it imparts an undesirable rigidity to the heel and frequently the rubber does not adhere well to the metal. The fibrous insert, which may be of canvas, leather or the like 30 must be of considerable thickness, or must consist of several plies, if the nail heads are to be prevented from pulling through, and such inserts are quite expensive, as compared with the total value of the manufactured heel.

It is the object of the present invention to provide a cushion heel which can be manufactured at a minimum cost and which shall possess the combined advantages of heels already known, without any of the attendant disadvantages. In the illustrated embodiment of the invention a rubber heel is provided which is as flexible and resilient as the ordinary isolated washer heel, in which the 45 nail head anchoring means is permanently inseparable from the rubber, and which may be manufactured very economically. As herein disclosed these results are secured by the provision of a plurality of flexibly connected nail holding inserts. These inserts,

which are preferably substantially rigid in themselves, may be mounted in properly spaced relation in a piece of suitable flexible material, for example, canvas, which may be handled as a unit and which is capable of 60 being vulcanized securely to the rubber or other material constituting the body of the heel. As herein illustrated, a plurality of eyelets are set, in a pattern corresponding to the desired nailing, in a mounting consisting of a skeleton piece of canvas of appropriate shape. This element may be placed in the vulcanizing mold, with the eyelets upon the mold pins, at a single movement; the rubber vulcanizes readily and securely 65 to the canvas; and, while a single layer of fabric of a comparatively cheap quality is sufficient, it aids very greatly in maintaining the eyelets in their proper positions in the rubber. 75

While the canvas mounting is sufficiently flexible not to impair the flexibility of a heel as a whole, it aids in distributing the pull of the nails upon the rubber and eliminates the tendency of individual nails to pull the 80 washers—or, in the present case, eyelets—loose from the rubber. The eyelets, set in the canvas mounting, afford a superior anchorage for the attaching nails and the attachment of the heel to a shoe is exceptionally secure. 85

Other features and advantages of the invention will be more clearly understood from reading the following detailed description of one satisfactory embodiment thereof in connection with the accompanying drawings, in which

Fig. 1 is a perspective view of a heel embodying the invention, with a portion cut away to show the interior construction; 95

Fig. 2 is a transverse section on the line 2—2 of Fig. 1 showing the heel attached to a shoe; and

Fig. 3 is a sectional detail showing a modified form of insert. 100

10 indicates the body portion of a cushion heel which may be made of rubber composition or any other suitable material capable of being vulcanized. For convenience in description the heel will hereinafter be referred to as a rubber heel, this term being understood to include any heel made of suitable equivalent material. 105

As illustrated, a D-shaped piece 12 of fibrous material is vulcanized in the heel and 110

constitutes a mounting for a plurality of eyelet-like metallic inserts 14, through which the attaching nails 16 are to be driven. The mounting 12 may be made of any suitable sheet material, such as fabric, leather, fibre or the like and may be of any preferred shape, as long as its form is such as to include within its surface area the points at which the desired number of eyelets 14 are to be located.

10 It has been found that a light grade of canvas or duck serves the purpose satisfactorily and can be utilized at a minimum cost.

The nail anchoring inserts 14 preferably consist of metallic eyelets set in the canvas by inserting and clenching them in a manner well known to those skilled in the art and so arranged and spaced that they will easily fit over the usual washer pins of a rubber heel mold. The support 12 with the eyelets 14 mounted therein may be inserted in the heel mold by a single motion, practically as quickly as one of the usual rubber heel washers; furthermore, being of substantial size, it is much easier to handle than the small washers generally employed. When it is realized that a rubber heel commonly contains from six to eight washers, which must be separately placed upon the mold pins, it will be appreciated that a great saving of time in this part 30 of the heel manufacturing process is effected by the present invention, as compared with the handling of individual washers.

The mounting member 12 may be quite flexible so as not to impart to the heel the objectionable rigidity which results from the use of metal plates of equivalent area, and it has the further advantage of greater durability since it is made of material to which the rubber can be securely and permanently vulcanized whereas the vulcanization of rubber to metal is more or less uncertain and the adhesion between the two is frequently insecure or temporary. While the mounting member 12 need not be as heavy or strong as would be necessary if it were to be depended upon exclusively to prevent the heads of the nails 16 from pulling through, yet the eyelets 14 which are engaged by the heads of the nails have a very firm hold upon the mounting 50 which is effective to distribute the strain of each nail over a considerable area.

Furthermore, as is well known, the spacing of the washer pins in rubber heel molds is not the same as the spacing of the corresponding holes in the nailing die of standard heeling machines by which the heels are attached, the reason for this being that the heels shrink materially in the curing process and suitable allowance for this shrinkage is made when the

pins are located in the mold. This lack of identity in spacing between the pins of the heel mold and the holes in the nailing die of the heeling machine gives rise to so much difficulty that heels provided with metal plates having their holes spaced to fit the mold pins 65 are unsuitable for machine attaching. The mounting member 12 herein described may be, however, sufficiently flexible to permit the heel to shrink naturally and specially designed molds are, therefore, not required to manufacture heels which are capable of proper nailing with a standard heeling machine.

While the drawings illustrate a rubber half heel used in combination with a rigid base section 18 and attached to a shoe 20, it should be understood that the invention is equally applicable to whole heels and to cushion heels of any form or shape.

Fig. 3 illustrates a modified form of eyelet 80 22 which has a conical surface 24 for guiding the point of a nail toward the central hole and which, in this respect, has the same advantages as the well known conical washer.

Having described the invention, what is 85 claimed as new and desired to be secured by Letters Patent is:—

1. A cushion heel having embedded therein a plurality of nail holding inserts and a mounting of sheet material different from 90 that of which the inserts are composed to which said inserts are secured.

2. A cushion heel having embedded therein a plurality of separate, nail engaging eyelets and a mounting member in which said 95 eyelets are inserted and clenched.

3. In a cushion heel, a piece of non-metallic sheet material having an eyelet set therein.

4. In a cushion heel, a piece of non-metallic sheet material having a plurality of separate 100 eyelets set therein.

5. A cushion heel having embedded therein a flexible mounting of sheet material and a plurality of separate, conical nail engaging eyelets inserted and clenched in said mounting.

6. A nail anchoring element for cushion heels comprising a sheet material mounting having a plurality of separate eyelets inserted and clenched therein in the pattern of 110 the desired nailing.

7. A rubber heel having vulcanized therein a piece of fabric in which are set a series of metallic eyelets arranged in the pattern of the desired nailing.

In testimony whereof I have signed my name to this specification.

CAMERON TURNER.
